APPARATUS FOR STRIPPING INGOTS

George A. Dornin, Baltimore, Md.

Application March 2, 1934, Serial No. 713,667

1 Claim. (Cl. 22—95)

This invention relates to the stripping of ingots, more particularly big-end-up ingots. Those who have worked out practical procedures for stripping ingots have heretofore adhered rather closely to certain well defined courses. Ingots cast with a sink-head or other projecting portion have presented a fairly simple problem, since mechanism can readily be devised for gripping the part of the ingot which projects above the top of the mold. It is obvious, however, that this procedure is inapplicable to the bulk of the tonnage of steel produced, as only a minor portion of this tonnage has a projecting part. Of the tonnage produced without sink-heads, nearly all is poured in big-end-down molds. Of the tonnage poured in big-end-down molds, a large proportion would be poured in big-end-up ingots if a simple mechanism could be purchased for stripping big-end-up ingots. One reason for this is that important economies could be effected with a big-end-up pouring procedure.

Considerable mechanism has been designed and a number of machines are in operation for stripping big-end-up ingots by holding the mold down and pushing the ingot up through the mold by a plunger which must be operated through the platform of the ingot-carrying car. It has been believed that the plunger must thus extend through the car platform if stripping is to be carried out with a minimum of cost for handling. While strippers have been built as independent units which require that the mold with its contained ingot be carried from the car and positioned on the stripping mechanism, this is a slow and costly procedure.

Correct principles for production of ingots on a large scale favor the retention of the ingot mold on a car until the ingot is ready to go to the soaking pit. In other words, economy in the production of ingots is largely a matter of minimum carrying or handling costs; as the heavy masses involved render this such an important item of expense.

Furthermore, an improved procedure has been developed for so treating ingots immediately following the pouring as to subject an incompletely solidified ingot to a soaking treatment within the ingot mold. Various proposals of this kind have been made looking to a more perfect grain structure or a modification of the formation within the ingot of the segregate. Preferably, the ingot is pushed up within the ingot mold to subject the upper portion of the ingot to a soaking treatment. The step of pushing the ingot up within the ingot mold while the

upper portion of the ingot is only partially solidified cannot be effected by mechanism which depends upon gripping a sink-head or other projecting part of the ingot. In accordance with my invention, I strip a partially solidified ingot by lowering the mold while engaging the ingot by a pin or other abutment which telescopes with the hole in the bottom of the mold, stopping further downward movement of the ingot.

Stripping mechanism which involves thrusting a plunger upwardly through the platform of the ingot carrying car renders the operation of the plant for producing ingots inflexible and expensive. In stripping big-end-up ingots it is not entirely satisfactory to lift the ingot relatively to the mold sufficiently to loosen the same and then allow the ingot to drop back within the mold. Such a step of loosening the ingot within the mold is all that is accomplished by a stripper having a plunger moving upwardly through the platform of the car and entering the bottom of the ingot mold. When the car carrying the molds reaches the soaking pit, the ingot must be again pushed up so that the top of the ingot may be grasped in removing the same from the mold for lowering into the soaking pit. This means that the ingot is twice pushed up within the ingot mold. Other types of strippers comprise a pin for each mold, this pin being pushed upwardly by the stripper and locked in raised position. Such stripping mechanism requires accurate registry of each pin with the plunger of the stripping mechanism, which is difficult to effect as a regular procedure.

Moreover, the pouring operation is most satisfactorily done with the train of cars carrying the ingot molds stationary; and this is the almost universal practice today. This means that an entire heat is poured and then transported to a different part of the plant where the stripping operation is performed. No procedure has as yet been perfected to the point of being practical which properly synchronizes the pouring and stripping so that at the proper interval after each mold is poured, the ingot is stripped, and at the same time the procedure is continuous so that an entire heat of ingots is produced in succession.

My invention provides such a simple procedure for stripping big-end-up ingots as to overcome one of the principal objections to pouring steel in big-end-up molds. Furthermore, my invention does not require movement of the train of cars along a trackway to bring the molds successively into cooperative relation with the stripping.

mechanism; since with the train of cars stationary, a crane may be moved longitudinally of the train to perform the stripping operation on each of the molds successively. My invention 5 contemplates stripping big-end-up ingots which have only partially solidified, and avoids the hazard of a caved-in top by engaging the bottom of the ingot in stripping.

Proposals have heretofore been made for stripping a big-end-up ingot by lowering the mold 10 so as to force a stripper plug up through the bottom of the mold into engagement with the ingot. The operation of such a stripping mechanism was never to my knowledge satisfactory since the 15 molds would topple, and it was the common thing for the mold to tilt over on the pin; and at times the mold would become completely disengaged from the crane so as to fall on its side. Obviously, such stripping mechanism would be extremely 20 dangerous if used to strip any ingot and impossible for use in stripping partially solidified ingots.

I have found that the reason for the unsatisfactory results obtained with this procedure was 25 that an essential step was omitted. The stripping of the big-end-up ingots, including such as have only partially solidified, by lowering the mold while guiding the same in a predetermined path and meeting the contained ingot with an obstruction to stop further downward movement of the 30 ingot while continuing the lowering and guiding of the mold is such a satisfactory procedure, and at the same time so simply performed in connection with the customary procedure for pouring 35 ingots that it opens the way for important economies in the pouring of a very large tonnage of steel in big-end-up ingots that is now poured in big-end-down ingots.

In the accompanying drawings which illustrate 40 my invention,

Fig. 1 is a view in end elevation of an ingot mold contained within a guideway structure, the ingot having been poured while the ingot mold is supported in raised position;

Fig. 2 is a fragmentary view of the lower portion of the ingot mold and structure shown in Fig. 1, this view showing a preparatory stage in the process of stripping with the ingot mold lifted above the stripping pin;

Fig. 3 is a view principally in central vertical section showing the ingot after it has been stripped;

Fig. 4 is a plan view of a guideway structure for cooperating with the molds during stripping, one 55 of the molds being shown in section;

Fig. 5 is a detail plan view illustrating one manner of guiding the stripping pin;

Fig. 6 is a perspective view of the slide carrying the stripping pin as embodied in Fig. 5;

Fig. 7 is a plan view of a modified form of guideway structure;

Fig. 8 is a vertical sectional view on the line VIII—VIII of Fig. 7;

Fig. 9 is a detailed view principally in side elevation of the lower portion of the stripping pin shown in Figs. 7 and 8;

Fig. 10 is a view principally in side elevation of mold manipulating mechanism cooperating with a guideway structure such as shown in Figs. 7 70 and 8, this mechanism being adapted to engage both the mold and the guideway structure simultaneously to effect relative movement therebetween;

Fig. 11 is a vertical sectional view on the line 75 XI—XI of Fig. 10;

Fig. 12 is a perspective view of the engaging arm of the mold manipulating mechanism;

Fig. 13 is a perspective view of the cross-head vertically movable within the arm and having portions engageable with the mold;

Fig. 14 is a plan view, and

Fig. 15 is a view in side elevation of a slide carrying a stripper pin;

Fig. 16 is a perspective view of a block carried by the slide shown in Figs. 14 and 15; and

Fig. 17 is a detail plan view showing the slide of Figs. 14 and 15 as related to positioning stops.

Figs. 1 to 9 inclusive illustrate simple apparatus for carrying out my invention with the use of a crane such as is usually available in a steel plant; 15 while Figs. 10 to 17 inclusive illustrate more completely organized apparatus for performing the stripping of big-end-up ingots in accordance with my invention.

The essential feature of my improved practice 20 is the guiding of the big-end-up ingot mold as it is moved downwardly in stripping the ingot. The guideway structures provided for this purpose which I have shown in the drawings are merely illustrative, as a designer can readily follow the principles of my invention and provide a suitable structure without adhering to the details disclosed herein. One embodiment is shown in Figs. 1 to 4 inclusive and includes a base plate or stool 20 carrying one or more abutments, which 30 herein take the form of pins 21. A simple manner of guiding the molds, and the one which I prefer, is to provide guiding means such as the projections or lugs 23 shown on the mold 24. With these lugs 23 cooperate vertical guideways for maintaining the mold 24 in proper alignment with the stripping pin 21 during lowering of the mold to strip the ingot. A suitable guideway is provided by parallel vertical elements suitably connected and braced by other portions of the guideway 35 structure. In the embodiment shown in Figs. 1 to 4 inclusive these vertical elements are the parallel flanges 26 and 27 and the web 28 (see Fig. 4), of a vertical H-beam 30. The lateral faces of the lugs 23 cooperate with the flanges 26 and 27, and the exterior faces of the lugs 23 cooperate with the webs 28, thus confining the mold during the stripping operation to vertical movement only.

In the embodiment shown in Figs. 7 and 8, the base plate or stool 20a carries guide posts 32 and 33 whose opposed faces engage the lateral faces of the lugs 23a and 23b, while the inturned faces of the guide posts 32 and 33 engage the guide surfaces 34 and 35 on the mold itself.

In order to provide a strong and rigid structure, 55 longitudinal braces 37 are secured to the H-beams 30, as by welding, and cross-braces 38 connect the longitudinal braces. In the embodiment shown in Figs. 7 and 8, a somewhat heavier longitudinal brace 40 connects the series of guide posts 32 and 33, and transverse braces 38a connect the longitudinal braces 40. Corner plates 41 may be welded in place, as illustrated in Fig. 7, to strengthen the longitudinal and transverse braces.

The guideway structure, as shown, may be 65 adapted to the particular plant where it is to be installed. It may be necessary with certain installations to strip the ingots in a stationary guideway structure, the same structure being in use continuously to perform the stripping operation. Accordingly, as broadly illustrated in Figs. 1, 2 and 3, no provision is made for transporting the base plate or stool 20. Generally, however, the guideway structure should be wheel-mounted 70 so that when the ingots have been pushed up 75

in the ingot molds, the same may be transported in the guideway structure to some other part of the plant, such as the soaking pit. Accordingly, there are illustrated in Fig. 8 the side rails 43 of 5 a car upon which stool 20a is mounted. It is obvious that if desired the guideway structure may be formed as an integral part of the car structure.

The abutment takes the form in Figs. 1, 2 and 10 3 of a stripping pin 21 which is fixed permanently in the stool 20. A shiftable pin is provided in the embodiments of the invention illustrated in Figs. 4 to 6 inclusive and in Figs. 10 to 16 inclusive, while in Figs. 7, 8 and 9 a 15 movable pin is illustrated. As shown in Figs. 5 and 6, a slide 45 carries adjacent one end a block 46 and adjacent the other end a stripper pin 47. The slide 45 is guided by lugs 48 on the base plate 20'. Stops 49 limit the travel of the 20 slide in either direction.

As illustrated in Figs. 10 to 16 inclusive, a segment 51 is pivoted to the stool 20a by a pin 52. The segment 51 carries a block 53 and a stripper pin 54. Stops 55 (see Fig. 10) limit 25 the swinging movement of the segment 51. It is apparent, therefore, that with the construction shown in Figs. 5 and 6 or with the construction shown in Figs. 10 to 17 inclusive, the pin is guided to operative and to inoperative position.

In its broadest aspect my invention is not concerned with the pouring of the ingots, as a guideway structure with cooperating abutment or abutments may be used in cooperative relation 35 with a crane to perform the necessary stripping operation on big-end-up ingots which have been poured according to the customary practice. It may, however, be of advantage to strip the ingots without the necessity for transporting the 40 molds to the guideway structure and inserting them therein. To pour the ingots with the big-end-up molds already positioned in the guideway structure, both the expedient illustrated in Figs. 1, 2 and 3 and the one illustrated in Figs. 4, 45 5 and 6 or Figs. 10 to 16 inclusive are suitable. For example, a block 58 may be interposed between the pin 21 and the bottom of the mold 24 as illustrated in Fig. 1, so as to support the mold in elevated position. The usual refractory 50 plug 60 being positioned in the customary opening 61 in the bottom of the mold, the ingot is poured and allowed to cool sufficiently to give the ingot the necessary skin strength for stripping. A crane whose arms are shown at 63 is 55 then engaged with the mold lugs to raise the mold slightly as illustrated in Fig. 2. The block 58 being withdrawn, the mold 24 is then lowered to cause the pin 21 to enter the opening 61, bringing about the stripping of the ingot without 60 the requirement for the application of any additional weight beyond the mass of the mold 24 itself in the great majority of cases. Should, as may happen in a few instances, the ingot stick in the mold, the arm 63 may be pressed 65 downwardly on the top of the mold 24 to force the mold downwardly and complete the stripping of the ingot 64.

An analogous procedure is illustrated in Figs. 4, 5 and 6; but with this embodiment, the ingot 70 molds 24 are in lowered position resting on the blocks 46 when the ingots are poured. A slide 45 is shown in Fig. 5 with the block 46 on the center line of the stool 20' in position for supporting a mold 24. When the stripping operation is to be performed, the mold 24 is lifted, as

by a crane or other suitable mold manipulating mechanism, and the slide pushed to the other end of its travel. With the pin 47 on the center line of the stool 20', the mold may be lowered to strip the ingot just as described in connection 5 with the embodiment of the invention illustrated in Figs. 1, 2 and 3.

The abutment illustrated in Figs. 7, 8 and 9 can be used either for the pouring procedure illustrated in Figs. 1, 2 and 3, or may be used 10 simply for stripping ingots which have been poured elsewhere in the plant. This abutment takes the form of a pin 65 having a base flange 66 for resting on the stool 20a. A head 68 extends downwardly into a socket 69 provided in 15 the stool 20a, and a projecting lug 70 cooperates with vertical and horizontal grooves 71 and 72 respectively to constitute a bayonet lock. This provides a simple manner of removably securing an abutment in the stool 20a of the guideway 20 structure.

In Figs. 10 to 13 inclusive is illustrated mechanism which can be employed for manipulating the molds in cooperation with the guideway structure illustrated in Figs. 10 and 11 is substantially the same as the embodiment illustrated in Figs. 7 and 8 and is likewise wheel-mounted. The mechanism cooperating therewith for manipulating the molds includes a top beam 75 30 acting as a cross-head slide for the stripper arms 77. The top beam 75 can be made from simple rolled shapes and plates, or may be made as one integral casting. Its elements, as shown in Fig. 10, include top and side plates 78 and 35 79, the side plates terminating in inturned flanges 80 so as to complete the slides for the supporting heads 82 of the stripper arms 77. A transverse web 84 reinforces the top beam at its central portions. Trunnions 85 extend 40 laterally from the beam so as to be readily engaged by the hooks of a crane. If desired, there may be provided in addition a lifting eye 86 on top of the beam, as shown in Fig. 11.

The arms 77 are constructed with two vertical 45 beams 83, connected at the top by a transverse web 87 and connected at the bottom by a transverse engaging member 89 for hooking under the longitudinal brace 40. The beams 83 are cut out above the engaging member 89 to provide recesses 90 for receiving the longitudinal brace 40. Thus there is a heel portion 91 on each beam 83 which may rest on top of the longitudinal brace 40.

The arms are constructed to provide a cross-head guide in the form of inwardly projecting 55 guides 93 on the arms 83. The cross-head 94 slides vertically on the guides 93, being raised and lowered by a screw 95 threaded through a nut 96. The periphery of the nut is formed as a worm 60 gear meshing with the threads of a worm 97. The nut 96 is rotatably mounted between anti-friction bearings 97a carried by upper and lower 65 housings 98 and 99. These housings are secured to a base plate 100 slidable on rails 101 and 102, as shown in Fig. 10. The flanges of the bed 70 plate 100 are inturned, as indicated at 104, to prevent lifting of the base plate when the nut 96 is rotated to force the screw 95 and cross-head 75 screw and nut, and the mechanism for rotating the nut will be duplicated on the other side of the cross-beam; and the two worms 97 may be driven individually, each by its own motor 106; or a single motor may be connected by a 75

cross-shaft slidably connected as by a spline to the driving gearing 107 for rotating the worm 91.

The cross-heads 94 are raised and lowered to manipulate the mold in the guideway structure; and for this purpose I provide a heel 109 and a toe 110 for engaging above and below a flange 111 on each side of the mold.

The arms 77 being hung from the supporting heads 82 are slidably toward and from each other in the guideways provided in the cross-beam 75. To effect such separation or inward movement of the arms, I rotatably mount a cross-shaft 113 in a bearing provided by a bracket 114. Collars 116, one to either side of the bracket 114, prevent transverse movement of the screw 113. Nuts 117 carried by the arms 77 cooperate with the screw 113 so that when the latter is rotated, the arms 77 are simultaneously moved inwardly or outwardly in accordance with the direction of rotation of the shaft 113, one nut being a right-hand nut and the other nut being a left-hand nut. A motor 119 mounted on the side of the beam 75 is connected by suitable gearing as a worm gear fixed to the screw 113 to rotate the same in either of opposite directions.

A number of advantages flow from the construction illustrated in Figs. 10 and 11. The heel 109 extends inwardly far enough so that the manipulating mechanism may be lowered over a guideway structure until the heels 109 engage the top of the flanges 111 of the mold. After the operator has become skilled in the operation of the mechanism, he can preliminarily move the screw 95 to proper position to cause the recess 90 to register with the brace 40. The screw 113 may then be rotated to bring the arms inwardly and engage the recesses 90 with the braces 40. At the same time, the toes 110 engage under the flanges 111 of the mold. The mechanism is thus connected both to the mold and to the guideway structure, and the mold may be positively moved vertically either upwardly or downwardly.

A further important advantage of the construction shown is that having once engaged the braces 40 in the recesses 90, the mold manipulating mechanism may be moved along the guideway structure to engage a series of molds successively and strip an entire car in a short space of time. Since the operator is called upon to position the manipulating mechanism with respect to the longitudinal brace 40 and the flanges of the molds but once for each car, it is obvious that the operation of stripping is considerably simplified.

The construction shown is considerably lighter than would be possible with ordinary types of stripping cranes, and is considerably less costly;

because during stripping the weight of the mold manipulating mechanism and of the mold itself, including the ingot, are borne by the longitudinal braces 40 through contact of the heel portion 91 with the top of the brace. If the mold sticks, the screw 95 comes into play to positively force the mold downwardly; and if necessary the transverse engaging member 89 can be drawn up against the bottom of the brace 40.

From the foregoing it can be readily seen that I have invented an extremely flexible method of stripping big-end-up ingots; and one that fits itself into present day steel plant equipment with a minimum of change. It can further be seen that the stripping operation can be performed at the pouring platform and when the ingot has only partially solidified, all that is necessary being a crane to lift and lower the mold within the guideway structure. It can be seen that if I so desire I can keep a guideway structure at the soaking pits on the ground, or conveniently placed; and by pouring the molds on the regular ingot cars, can perform the stripping operation at the pits with the regular pit cranes. This procedure involves merely taking the mold off the ingot car, lowering it into the guideway structure, charging the ingot, and returning the now empty molds to the ingot car. All of these operations can be performed by the regular charging cranes where time permits. The stripping operation can also be performed at any point between the pouring platform and the pits, all that is necessary being a crane to move the molds and contained ingots up and down within the guideway structure; and this can be performed by a locomotive crane on an adjoining track if desired.

While I have illustrated and described certain embodiments which my invention may assume, it will be understood that my invention is not restricted to the particular constructions and arrangements shown, but may be variously modified within the contemplation of the invention and under the scope of the following claims.

I claim:

Apparatus for stripping ingots comprising a wheel mounted support, a structure on said support providing vertical guideways for guiding a mold in raising and lowering movements relative to said support and restraining lateral movement of the upper portion of the mold, a projection for entering an opening in the bottom of the mold when the mold is in lowered position relative to said structure, and means cooperating with said projection for supporting said mold in sufficiently elevated position to maintain the mold cavity freed from said projection.

GEORGE A. DORNIN.
